APPARATUS FOR WINDING COILS

Edward Snyder, Fort Wayne, Ind., assignor to
General Cable Corporation, New York, N. Y.,
a corporation of New Jersey

Application December 20, 1929, Serial No. 415,441

10 Claims.

(Cl. 242—72)

This invention relates generally to a method of and apparatus for winding coils of wire, and more particularly to an expansible and collapsible mandrel and a method for making layer wound coils.

It is an object of this invention to provide an improved mandrel for winding layer wound coils of the type in which the turns of the first layer are positively positioned on the mandrel in accordance with a predetermined plan, and the turns of the succeeding layers lie, except for short distances at points of cross-over, in the grooves between the turns of the immediately preceding layer. A further object is to provide an improved method of winding coils of the type described. Other objects and advantages of the invention will appear hereinafter.

An illustrative embodiment of the invention selected merely for descriptive purposes is shown in the accompanying drawing, in which:

Fig. 1 is a side view of the mandrel in expanded condition, a portion of the mandrel being broken away to show a longitudinal section; Fig. 2 is an end view taken from the right hand end of Fig. 1, the end flange 11 being removed, and a portion of the mandrel broken away to show more clearly the construction of the mandrel;

Fig. 3 is a view of the mandrel similar to Fig. 1, the mandrel being in collapsed condition; and Fig. 4 is an end view of the mandrel substantially on line 4—4 of Fig. 3, a portion of the mandrel being broken away to disclose the construction.

In winding multiple-layer coils in which the layers are not spaced from each other, as by means of sheets of insulating material, it will be apparent that for a coil having a fixed number of turns of a given size and kind of wire the cross-sectional area of the coil wall transverse to the direction of the coil turns may be reduced to a minimum only when the space between adjacent coil turns is reduced to a minimum.

In winding coils of round wire, the space between coil turns may be reduced to a minimum only when each turn of the coil is wound accurately in accordance with a predetermined plan utilizing the available space to the best advantage. Preferably, the turns of the first coil layer lie, except for short distances at the points of cross-over between turns, in planes perpendicular to the longitudinal axis of the coil, and are spaced from wire center to wire center a

distance slightly greater than the maximum wire diameter. The turns of the succeeding layers lie, except for short distances at the points of cross-over, in the grooves between the turns of the preceding layer. Such a coil will have smaller overall dimensions than a coil of the same number of turns and kind of wire wound in some other manner, and consequently will require less wire for a given number of turns.

Referring to Figs. 1 and 3, a spindle 16 supports a hub 2. The hub 2 may be permanently attached to the spindle 16, or, preferably, the hub 2 may be removably secured to the spindle in any desirable manner. The spindle 16 will be connected to a suitable source of driving power so that it can be rotated when a coil is to be wound. Conveniently, the spindle 16 may be the winding spindle of a coil winding machine, or it may be the shaft of an electric motor.

At its outer end the hub 2 is provided with a head flange 1. As may best be seen in Figs. 2 and 4, the flange 1 preferably has two or more radial slots 17 which permit the positioning of clamping bars as hereinafter described to prevent unwinding of the completed coil when the mandrel is collapsed and the coil is removed from the mandrel.

The head flange 1 has a central bore into which one end of each of the arcuate-shaped mandrel core members 4 and 5 extend. The central bore limits outward radial movement of the core members when the mandrel is expanded in the manner hereinafter described. The core members 4 are substantially semi-cylindrical in form, and the outer surfaces of the core members 4 preferably are smooth. The longitudinal edges of the core members 4 are tapered inwardly, and the core members 5 are tapered in the reverse direction and extend along and lie between the adjacent edges of the members 4. Because of the tapered edges of the core members 4 and 5, radial movement of the members 5 outwardly will force the members 4 apart and expand the mandrel.

As may be seen in Figs. 2 and 4, the end of each of the members 4 which projects into the bore of the head flange 1 is provided with a radial outwardly extending pin 6. These pins 6 are slidably received in radial guideways 7 in the end flange 1. A spiral spring 9 in each of the guideways 7 bears against the outer end of the pin 6. The springs 9 are maintained under compression, as by means of the threaded plugs 8, and normally tend to force the pins 6 and

the core members 4 radially inward to collapse the mandrel core.

Referring to Figs. 1 and 2, the ends of the core members 5 which project into the central bore 5 of the head flange 1 have screw threaded radial passageways which are engaged by the inner ends of the screws 10 which extend through radial openings in the flange 1. It will be seen that when the screws 10 are turned in the direction to 10 move the members 5 radially outward, the core members 4 will be forced apart and the mandrel will be expanded. When the screws 10 are turned in the opposite direction the members 5 will be permitted to move radially inward, 15 whereupon the core members 4 will be forced radially inward under the influence of the springs 9 to collapse the mandrel.

The members 5 are provided along their outer edges with a plurality of equally spaced grooves 20 preferably lying in planes perpendicular to the longitudinal axis of the mandrel, and with the grooves of one member circumferentially aligned with the grooves of the other member. When the tapered members 5 are moved radially outward to expand the mandrel, the ridges between the grooves along the outer edges of the members 5 project outward a slight distance beyond the adjacent, smooth, circumferential faces of the members 4. The spacing of the grooves from 30 root center to root center preferably is substantially equal to or slightly greater than the diameter of the wire which is to be wound on the mandrel. In practice there are slight variations in wire diameter, even in short lengths of 35 wire, and for this reason it is desirable to make the spacing of the grooves slightly greater than the maximum wire diameter, for example 1½ to 2½% greater. Since the ridges between the grooves project out from the face of the mandrel core, the ridges will individually engage the turns in place.

When the mandrel is in collapsed condition, 45 the ridges along the outer edges of the tapered members 5 are completely submerged between the adjacent edges of the members 4. Consequently, when the mandrel is collapsed, a coil can be slid off of the mandrel without having 50 the inner layer of turns scraped by the wire holding ridges. It will be apparent that this feature lessens the danger of breaking the insulation or displacing coil turns during the operation of removing a coil from the mandrel.

As may be seen in Figs. 1 and 3, a tail flange 55 11 is provided for engaging the free ends of the core members 4 and 5, and suitable means are provided for forcing the tail flange against the ends of the core members during the expansion 60 of the mandrel and the coil winding operation. By way of example, the tail flange 11 is secured on one end of a spindle 12 which is aligned with the spindle 16, and is longitudinally adjustable with respect thereto.

The tail flange 11 is provided on its inner face 65 with a frusto-conical shaped centering stud 13, and an annular recess 14 encircling said stud. The inner edges of the core members 5 are tapered at their free ends so that as the tail flange 70 11 is moved toward the mandrel core the centering stud 13 enters between the ends of the members 5 and forces them apart and radially outward to expand the mandrel. The outward movement of the members 5 is limited by the engagement of the ends of the core members

4 and 5 with the outer wall of the annular recess 14.

The tail flange 11 preferably is provided with two or more radial slots 18 which are angularly aligned with the radial slots 17 in the head 80 flange 1. After a coil has been wound on the mandrel, U-shaped clamping bars may be positioned on the coil winding, the legs of the clamping bars entering the radial slots 17 and 18 and engaging the ends of the coil. After the 85 clamping bars have been so positioned, the tail flange 11 may be withdrawn from the mandrel core, the mandrel collapsed, and the coil removed therefrom without danger of the end 90 turns of the coil moving out of position.

Fig. 3 shows the mandrel in collapsed condition, with the tail flange 11 withdrawn from the end of the mandrel core. To expand the mandrel preparatory to winding a coil, the spindle 12 and the tail flange 11 will be moved to the 95 left, the centering stud 13 engaging the tapered inner edges of the members 5 to force these members radially outward, thereby forcing the members 4 radially outward and expanding the mandrel. The screws 10 are turned to draw and hold the other ends of the members 5 radially outward to insure complete expansion of the mandrel, as shown in Fig. 1.

In winding a coil upon the mandrel, the mandrel is first expanded. The end of the 105 wire from the supply spool is secured on the hub 2 or spindle 16 in any suitable manner, as by wrapping two or three turns about the hub 2. In the embodiment disclosed the wire will be secured on the head flange end. The wire is 110 then carried into the angle between the mandrel core and the head flange 1, either through one of the radial slots 17 or through another radial slot provided for this purpose. The spindle 16 is then rotated, the first turn of the coil falling 115 in the angle between the flange 1 and the mandrel core, and being positively held there in a plane perpendicular to the longitudinal axis of the mandrel by the head flange, the ridges on the members 5, and the tension applied to the 120 wire as it is drawn onto the mandrel. Upon the substantial completion of the first full turn the wire by reason of the tension exerted on it and its riding up on the first part of the turn, is caused to move longitudinally along the mandrel a distance equal to the diameter of the 125 wire, and the second turn is wound parallel and immediately adjacent to the first turn. Further rotation of the mandrel results in the winding of additional turns along the mandrel. 130

It will be seen that the turns of the first coil layer lie in planes perpendicular to the longitudinal axis of the mandrel except at the points of cross-over, and that each turn is held in place at circumferentially spaced points by the 135 ridges 15.

If the distance between the mandrel and the wire supply or wire guide is not too short relative to the length of the coil to be wound, the wire will move automatically from one groove to the next groove when the wire engages the first part of the turn, and no additional means will be required for causing the wire to move longitudinally along the mandrel. In other cases it may be found desirable to provide a suitable 140 transversing wire guide moving back and forth parallel to the rotating mandrel to insure the desired laying on of the wire in the grooves.

When the last complete circumferential groove on the mandrel core has been filled, the 150

wire will ride up on the top of the first coil layer, and, under tension, will fall into a groove between either the last turn of the first layer and the tail flange, or in the groove between the last two turns of the first layer. The course taken here by the wire is dependent upon whether the last groove on the wire receiving core brings the last turn of the first layer one half a wire diameter distant from the tail flange, or flush against the tail flange. If the last groove of the wire-receiving mandrel core is a full groove, the even numbered layers of the coil will each have one less turn than the odd numbered layers, while if the last groove of the core is a half groove each coil layer will have the same number of turns. In the embodiment shown the last groove is a half groove. Upon further rotation of the mandrel the second and following coil layers are wound as was the first, the turns of the preceding layers serving as the wire positioning ridges.

When the desired number of turns are wound on the mandrel, rotation of the mandrel is stopped, the wire is severed and its ends is suitably secured to prevent unwinding, the inner coil lead is loosened from the hub 2, and the clamping bars are positioned on the coil as hereinbefore described. The tail flange is then withdrawn from the mandrel core, and the mandrel is collapsed by loosening the screws 10. The coil may then be removed from the mandrel core and tied to hold the turns in place, after which the clamping bars may be removed.

This invention provides a mandrel which is simple in construction and operation, and which is adapted to wind accurately and at high speed layer wound coils having minimum overall dimensions. The mandrel may be readily expanded and collapsed, thereby permitting rapid winding of coils. The narrow grooved zones extending longitudinally along the mandrel surface positively position and hold the turns of the first coil layer in place, and the turns of succeeding layers are laid in the grooves between adjacent turns of the immediately preceding layer. The mandrel is readily adaptable to use for winding coils of various sizes, and the same head and tail flanges may be used for different size coils. In this latter case it merely will be necessary to substitute different arcuate shaped members for those already attached to the head flange.

It will be understood that the invention may be variously modified and embodied within the scope of the following claims.

I claim:

1. An expandable and collapsible coil winding mandrel comprising, in combination, two substantially semi-cylindrical members having their longitudinal edges tapered inwardly, an end flange, means securing said members at their ends on one face of said flange to form a substantially cylindrical coil-receiving core, said securing means permitting relative movement of the members radially of the end flange, means normally tending to move said members toward each other to collapse the mandrel, tapered members extending longitudinally along and between adjacent edges of said semi-cylindrical members, said tapered members being grooved transversely to their longitudinal axes along their outer edges, a second end flange for said core, and means for moving said tapered members radially outward to force said semi-cylindrical members apart and expand the mandrel.

2. An expandable and collapsible coil winding mandrel comprising, in combination, a plurality of arcuate shaped sectional members forming a substantially cylindrical core, certain of said members having smooth outer surfaces, and certain others of said members being provided on their outer surfaces with means projecting out beyond the smooth surfaces of adjacent members when the mandrel is expanded for positively positioning turns of wire, end flanges for said core, and means for moving the wire positioning members radially inward below the smooth outer surfaces of adjacent smooth-surfaced members to collapse the mandrel.

3. An expandable and collapsible coil winding mandrel comprising, in combination, two end flanges, a plurality of arcuate shaped sectional members extending between said flanges and forming a smooth, substantially cylindrical core, a plurality of narrow members extending between said flanges and lying between adjacent edges of said sectional members, said narrow members having a plurality of parallel, transverse wire-positioning ridges along their outer edges, and means for moving said narrow members radially of the core to cause the ridges either to project above or to be depressed below the smooth outer surface of the core.

4. An expandable and collapsible coil winding mandrel comprising, in combination, a plurality of arcuate shaped sectional members, an end flange, means securing each of said arcuate shaped members at one end to the end flange so that the arcuate shaped members form a substantially cylindrical core, means for bodily adjusting said arcuate shaped members radially relative to the end flange while preventing longitudinal displacement of said members relative to the end flange, a second end flange, and means for securing said second end flange against the free end of the core, the expanded mandrel core having throughout its length between end flanges a circumferentially continuous wire receiving surface and the collapsed mandrel core having throughout its length between end flanges a circumferentially discontinuous surface.

5. An expandable and collapsible coil winding mandrel comprising, in combination, a plurality of arcuate shaped sectional members forming a substantially cylindrical core, means securing said members at one end of the core to an end flange, said means permitting radial expansion and collapse of the core uniformly throughout its entire length, and a second end flange having a frusto-conical hub adapted to enter the free end of the core to expand the mandrel.

6. An expandable and collapsible coil winding mandrel comprising, in combination, a plurality of arcuate shaped sectional members, an end flange, and means securing each of said arcuate shaped members at one end to the end flange so that the arcuate shaped members form a substantially cylindrical core, said securing means permitting radial adjustment of said arcuate shaped members uniformly throughout their entire length relative to the end flange without longitudinal movement.

7. An expandable and collapsible coil winding mandrel comprising, in combination, a plurality of arcuate shaped sectional members separated from each other by a plurality of tapered spacing members, the assembly forming a substantially cylindrical core, the outer surfaces of the

- arcuate shaped members being smooth, and the outer surfaces of the spacing members being grooved in planes perpendicular to the longitudinal axis of the core.

5 8. An expandible and collapsible coil winding mandrel comprising, in combination, a plurality of arcuate shaped sectional members separated from each other by a plurality of tapered spacing members, the assembly forming a substantially cylindrical core, the outer surfaces of the arcuate shaped members being smooth, and the outer surfaces of the spacing members being grooved in planes perpendicular to the longitudinal axis of the core for positively positioning each turn of the first coil layer, the grooves of the spacing members being circumferentially aligned, and means for moving said spacing members to expand and collapse the mandrel.

10 9. An expandible and collapsible coil winding mandrel comprising, in combination, a plurality of arcuate shaped sectional members assembled to form a substantially cylindrical core, certain

15 20 25 30 35 40 45 50 55 60 65 70 75 80 85 90 95 100 105 110 115 120 125 130 135 140 145 150

of said members having a smooth outer surface, the aggregate extent of said smooth surface being greater than half of the total cylindrical surface of the core, certain others of said members being provided with outer surfaces which are grooved in planes perpendicular to the longitudinal axis of the core for positively positioning the turns of the first coil layer, the grooves of said grooved members being circumferentially aligned.

10. An expandible and collapsible coil winding mandrel comprising, in combination, two end flanges and a coil receiving core composed of a plurality of segments which, when expanded, provide a circumferentially continuous wire receiving surface, some of said segments having smooth outer surfaces and others of said segments having projections for individually positioning the coil turns, and means for moving said latter segments inwardly of the core to collapse the mandrel and free the coil.

EDWARD SNYDER.
